UNITED STATES PATENT OFFICE.

WILLIAM HUGH WOODCOCK, OF LONDON, ENGLAND.

ROLLER-BEARING.

SPECIFICATION forming part of Letters Patent No. 583,965, dated June 8, 1897.

Application filed August 22, 1896. Serial No. 603,605. (No model.)

To all whom it may concern:

Be it known that I, WILLIAM HUGH WOODCOCK, a subject of the Queen of Great Britain and Ireland, residing at 25 Auckland Hill, 5 West Norwood, London, in the county of Surrey, England, have invented new and useful Improvements in Roller-Bearings, of which the following is a specification.

My invention has reference to improvements in roller-bearings, having for its object to diminish friction between revolving journals or shafts and their bearings; and it consists in the novel construction and combination of the parts hereinafter fully described 15 and claimed.

In the drawings, Figures 1, 2, 3, 4, 5, and 6 represent the application of my first-mentioned improvement to a railway axle-box, the left half of Fig. 1 being a front elevation 20 and the right a back elevation, Fig. 2 being a part longitudinal section, Fig. 3 being on the left half a cross-section on center line and on the right half a cross-section on line A B, Fig. 2. Fig. 4 shows on the upper half a 25 sectional plan on center line of a railway axle-box, the lower half being an outside plan on top. Fig. 5 illustrates a cradle constructed according to my invention, suitable to cases where the rollers are inserted from the outside; and Fig. 6 is on the left half a cross-section on center line and on the right half a 30 cross-section on line A B, Fig. 2, of a cradle suitable to cases where the rollers are inserted from the inside.

Referring to the drawings, *a* is the journal 35 at the end of the axle of a railway-vehicle.

b is the axle box or casing, preferably made of cast-steel.

c c are the rollers, placed between the journal and the casing. 40

d is the metal cradle.

e are the projecting circular ribs formed upon the ends of the cradle.

f f are the corresponding circular ribs formed upon the casing. 45

g g are the faces formed on the inner sides of the ends of the cradle, which control the lateral movement of the rollers *c c* within the said cradle.

h h in Fig. 5 are the bearing-surfaces for 50 the rollers, formed on the spokes *i* of the cradle *d*, suitable to cases where the rollers are inserted from the outside of the cradle, and *k k* in Fig. 6 are the similar bearing-surfaces 55 suitable to cases where the rollers are inserted from the inside of the cradle.

What I claim is—

The combination, with a cylindrical axle-box provided with a circular rib *f* at its inner end, of a journal arranged concentric with 60 the axle-box, a cap secured to the axle-box over the end of the said journal and provided with a circular rib *f*, rollers arranged between the said journal and axle-box, and a cradle provided with end portions bearing against 65 the said ribs *ff* and preventing the said rollers from moving endwise, said cradle also having spokes extending between the said rollers and keeping them apart, substantially as set forth.

WILLIAM HUGH WOODCOCK.

Witnesses:

WILLIAM H. LEWERE,

WILLIAM J. THORN.
